2 Sheets-Sheet 2

<img alt="Fig. 2. A technical cross-sectional diagram of a mechanical assembly. The diagram shows a central horizontal plate with a grid of circular holes. Above this plate is a horizontal beam with a central slot. Two vertical rods, labeled 34 and 36, are attached to the beam. Rod 34 is connected to a lever system on the left, which includes a handle 42 and a spring 47. Rod 36 is connected to a lever system on the right, which includes a handle 40 and a spring 49. The entire assembly is mounted within a frame with various labeled parts like 1, 6, 7, 8, 9, 10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 299, 300, 301, 302, 303, 304, 305, 306, 307, 308, 309, 309, 310, 311, 312, 313, 314, 315, 316, 317, 318, 319, 319, 320, 321, 322, 323, 324, 325, 1284, 1285, 1286, 1287, 1288, 1289, 1289, 1290, 1291, 1292, 1293, 1294, 1295, 1296, 1297, 1298, 1299, 1299, 1300, 1301, 1302, 1303, 1304, 1305, 1306, 1307, 1308, 1309, 1309, 1310, 1311, 1312, 1313, 1314, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, 1911, 1912, 1913, 1914, 1915, 1916, 1917, 1918, 1919, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1959, 1959, 1960, 1961, 1962, 1963, 1964, 1965, 1966, 1967, 1968, 1969, 1969, 1970, 1971, 1972, 1973, 1974, 1975, 1976, 1977, 1978, 1979, 1979, 1980, 1981, 1982, 1983, 1984, 1985, 1986, 1987, 1988, 1989, 1989, 1990, 1991, 1992, 1993, 1994, 1995, 1996, 1997, 1998, 1999, 1999, 2000, 2001, 2002, 2003, 2004, 2005, 2006, 2007, 2008, 2009, 2009, 2010, 2011, 2012, 2013, 2014, 2015, 2016, 2017, 2018, 2019, 2019, 2020, 2021, 2022, 2023, 2024, 2025, 2026, 2027, 2028, 2029, 2029, 2030, 2031, 2032, 2033, 2034, 2035, 2036, 2037, 2038, 2039, 2039, 2040, 2041, 2042, 2043, 2044, 2045, 2046, 2047, 2048, 2049, 2049, 2050, 2051, 2052, 2053, 2054, 2055, 2056, 2057, 2058, 2059, 2059,

Inventor

C. E. Ayres

By

Lacey Thaey, Attorney

UNITED STATES PATENT OFFICE.

CLAUDE E. AYRES, OF AXTELL, NEBRASKA.

COLANDER.

Application filed December 3, 1925. Serial No. 73,015.

This invention relates to colanders and one object of the invention is to provide a colander which may be connected with a table or other suitable support and held stationary above the top of the table so that as material to be strained is forced through the colander it may be received in a receptacle placed upon the table beneath the colander.

10 Another object of the invention is to so form the operating means for forcing the material through the colander that the material may be easily and quickly forced through a perforated bottom of the colander.

15 Another object of the invention is to so mount the operating means that it will be yieldably held in the proper operative relation to the perforated bottom of the colander but permitted to yield upwardly so that 20 blades forming part of the operating means may pass over seeds resting upon the bottom of the colander.

Another object of the invention is to so 25 form the perforations in the bottom of the colander that the inner face of the bottom will be irregular and thereby provide ridges which will engage with the fruit being operated upon and cause the fruit to be readily forced through the outlet openings.

30 Another object of the invention is to so mount the bottom of the colander that it will be firmly held in operative relation to the body portion thereof but permitted of being easily and quickly removed and thoroughly cleaned.

This invention is illustrated in the accompanying drawings, wherein—

Figure 1 is a perspective view of the improved colander;

Fig. 2 is a vertical sectional view taken longitudinally through the colander;

Fig. 3 is a vertical transverse sectional view through the colander.

45 Fig. 4 is an enlarged view showing one of the table-engaging clamps in side elevation and in gripping engagement with a table top shown in section, and

Fig. 5 is a fragmentary perspective view 50 illustrating the manner of connecting one end of the colander bottom with the body of the colander.

The body portion or receptacle 1 is preferably formed of sheet metal but may be formed of any material desired. This receptacle or housing is rectangular in shape 55 and provided with end walls 2 and 3 and side walls 4 and 5. The side and end walls may be of any desired depth according to the quantity of material which it is desired to have the colander receive and these walls 60 have their upper edges flush with each other so that the cover or lid 6 which closes the open upper end of the housing may fit in flat contacting engagement with the upper edges of the walls, as shown in Figs. 2 and 3. Depending flanges 7 are formed at the ends and sides of the cover to engage the side and end walls of the housing and retain the cover firmly in place. A handle 8 of a conventional construction is carried by the 70 cover so that the cover may be readily applied to the housing or removed. Referring to Figs. 1 and 3, it will be seen that the end walls 2 and 3 extend downwardly below the lower edges of the side walls 4 and 5 and formed with arcuate edges. These extended lower end portions of the end walls are substantially semi-circular in shape and are adapted for engagement with the arcuate trough-like bottom 9 adjacent the ends of the bottom. At its ends the bottom is formed with flanges 10 which overlap the outer faces of the depending lower end portions of the end walls so as to form tight joints and prevent the material being passed 80 through the colander from forcing the lower end portions of the end walls out of proper engagement with the bottom.

A rod 11 is secured transversely of the wall 4 near its lower end, as shown in Fig. 90 3, and has its end portions projected outwardly from the end walls 2 and 3 for engagement by hooks 12 provided at the ends of the bottom at one side thereof. These hooks 12 are preferably formed from wire 95 strands which extend along the flanges 10 and may be secured by having the flanges rolled over them. They may extend the full length of the flanges or only for a portion thereof but it is important that the wires 100 from which the hooks are formed be projected from the flanges and bent to form bills for engagement with the projected ends

of the rod 11. At its other side the bottom carries threaded stems 13 which project from its side edge and are adapted to be engaged with the outstanding flanges 14 of the clips 15 secured against the wall 5 of the housing. These stems 13 carry securing nuts 16, and it will be readily understood that, when the hooks 12 are engaged with the projected ends of the rod 11 and the stems 13 engaged with the clips and the nuts 16 tightened, the bottom will be firmly held in place and the depending end portions of the end walls of the housing prevented from being bulged outwardly by the material 15 forced through the colander. The bottom is formed with perforations 17 constituting outlets for the material, and referring to Figs. 2 and 3 it will be seen that, when the perforations are formed, the material of the bottom about the perforations or outlet openings is forced inwardly. This causes the bottom to have an irregular inner surface and forms ridges about the openings which will tend to engage the material to be passed through these openings and cause its movement across the bottom to be retarded and the material more readily forced through the openings.

In order to support the receptacle or housing in spaced relation above the table 18, there has been provided a bracket which includes standards 19 held in spaced relation to each other by a cross bar 20. Arms 21 extend from the upper ends of the standards 19 and are secured against the outer faces of the end walls 2 and 3 by rivets 21' or in any other desired manner. These arms are prevented from being bent downwardly by the weight of the receptacle and material placed therein by diagonally extending braces 22. At their lower ends the standards 19 are formed with clamps 23 having upper and lower arms 24 and 25. The arms 25 which constitute stationary jaws 45 rest upon the upper face of the table top and the lower arms extend beneath the table top and each terminates in a bearing 26 to receive a set screw 27. The set screw extends upwardly and terminates in a spherical head 28 received in a socket 29 formed upon the under face of a movable jaw 30 adapted to engage the under face of the table top when the set screw is tightened. At one end the movable jaw is slidably engaged with a rib 31 formed upon the vertically extending portion 32 of the clamp so that the movable jaw will be prevented from turning out of its proper position with respect to the stationary jaw. The colander can, therefore, be readily applied to a table top and firmly anchored in engagement therewith.

The operating means, by means of which the material to be strained is forced through the perforations in the bottom of the col-

ander consist of a paddle wheel which is rotatably mounted in the housing. The hub 33 of the paddle wheel is mounted upon a shaft 34 and held against turning thereon by means of a key 35 which passes through the hub and shaft intermediate the length of the hub. The hub is of sufficient length to fit snugly in the housing between the bearings which are indicated in general by the numeral 36 but the shaft is of greater length and has its end portions extending externally of the housing through vertically elongated openings 37 formed in the end walls 2 and 3. At one end the shaft is formed with a rigid collar 38 and at its other end it carries a collar 39 which is placed upon the protruding end of the shaft and secured in a set position by a set screw 40. It will thus be seen that the shaft may be prevented from having longitudinal movement and at the same time permitted to turn freely in the bearings. The handle 41, by means of which the shaft is rotated may be fitted upon a squared end portion 42 of the shaft and secured by a set screw if desired or the end portion of the shaft which receives the crank handle may be threaded and the handle have threaded engagement with the shaft. Arms 43 extend radially from the hub 33 of the paddle wheel and have their outer free end portions 44 bent to extend diagonally of their inner end portions and flattened to form feet against which the blades 45 are secured. These blades extend longitudinally of the receptacle or housing and since the outer end portions of the arms or spokes 43 are inclined, as shown in Fig. 3, the blades will be disposed substantially tangentially of the arcuate bottom 9 as they move across the bottom and will move the material across the bottom of the colander in such a manner that it will be engaged against the uneven inner surface of the bottom and readily forced through the openings.

The bearings, by means of which the shaft is rotatably mounted each includes an outer plate 46 which has flat contacting engagement with the outer face of an end wall of the receptacle in covering relation to the opening 37 formed therein. A stud 47 extends inwardly from the outer plate 46 through the opening 37 with its inner end portion extending inwardly of the receptacle wall and carrying an inner plate 46' which has close contacting engagement with the inner face of the receptacle wall in covering relation to the opening formed therein. The inner plate may be held upon the stud in any desired manner. In view of the fact that the openings formed in the end walls of the receptacle are covered by the inner and outer plates of the bearings, these openings are sealed in a very effective manner and the passage of material through them prevented.

It is desired to normally retain the operating element or paddle wheel in the position shown in Fig. 3 so that its blades will move in a path close to the inner surface of the bottom 9 but permit the blades to move away from the bottom in case a large seed or other obstruction is encountered and thereby prevent the blades from becoming wedged. If the blades became wedged, there would be danger of them being bent or other portions of the operating means broken. In order to yieldably retain the operating means in the normal position shown in Fig. 3, there has been provided springs 48 which have their upper ends engaged with hooks 49 attached to the outer plates of the bearings, as shown in Fig. 2, or formed by cutting tongues from the plate and bending these tongues outwardly, as shown in Fig. 1. The lower ends of the springs 48 are engaged with hooks 50 secured to the outer faces of the end walls near their lower ends and as the springs exert a downward pull they will yieldably hold the bearings against upward movement and normally retain them in engagement with the abutments 51 secured to the end walls. While each bearing has been shown engaged by two springs extending downwardly therefrom in diverging relation, it will be understood that if desired each bearing could be engaged by a single spring which would be disposed intermediate the width of the outer plate and engaged with the plate and end wall of the housing above and below the abutment 51.

When this colander is in use it is attached to the table, as shown in Figs. 1 and 4, and a dish or other receptacle placed upon the table beneath the colander. The material to be strained is poured into the receptacle after the cover has been removed and the cover then replaced so that the material will not be thrown out of the receptacle as the operating element or paddle wheel is rotated. The paddle wheel is now rotated by means of the crank handle and as it turns the blades will engage the material in the receptacle and cause it to be moved across the bottom circumferentially thereof. This will cause the material to engage against the uneven surfaces of the bottom and it will be readily forced through the outlet openings in the bottom. The skins or seeds of the fruit will, of course, remain in the colander. After all of the material has been strained through the openings, the receptacle placed beneath the colander is removed and the colander can then be detached from the table and cleaned by running water through it after the bottom has been removed. It will, therefore, be seen that the colander is so constructed that material can be readily strained through it and that if a seed or other obstruction is encountered by one of the blades there will be no danger of the colander being broken as the paddle wheel will be permitted to move up-

wardly against the action of the springs 48 and pass the obstruction.

Having thus described the invention, I claim:

1. A colander comprising a housing having opposed walls and a bottom formed with outlet openings, an operating element in said housing, and bearings to rotatably support said operating element, said bearings being slidably supported by said walls and yieldably held against movement away from said bottom.

2. A colander comprising a housing having opposed walls and an arcuate bottom formed with outlet openings, the material of said bottom being forced inwardly about the openings to provide an irregular inner surface for the bottom, and a rotary operating element in said housing including a hub having arms extending therefrom and blades carried by said arms and extending longitudinally of the bottom and having movement circumferentially thereof adjacent its inner surface and when the operating element is rotating, and bearings rotatably supporting said operating element, said bearings being slidably supported by said opposed walls and yieldably held against movement upwardly from said bottom.

3. A colander comprising a housing having an arcuate bottom formed with outlet openings, the material of said bottom being forced inwardly about the openings to provide an irregular inner surface for the bottom, a rotary operating element in said housing including a hub having arms extending radially therefrom with their outer end portions inclined to extend substantially tangentially of said arcuate bottom, and blades carried by the inclined end portions of said arms and having movement circumferentially of said bottom adjacent its inner surface when the operating element is rotating.

4. A colander comprising a housing having an arcuate perforated bottom and end walls formed with vertically elongated openings, a rotary operating element in said housing having a shaft extending through the openings of said walls, bearings for said shaft slidably carried by said walls in covering relation to said openings, and resilient means yieldably resisting upward movement of said bearings.

5. A colander comprising a housing having an arcuate perforated bottom and end walls formed with vertically elongated openings, bearings slidably carried by said walls in covering relation to said openings, means for limiting downward movement of said bearings, a rotary operating element in said housing and journaled in said bearings, and springs yieldably resisting upward movement of said bearings.

6. A colander comprising a housing having an arcuate perforated bottom and end

walls formed with vertically elongated openings, bearings slidably carried by said walls in covering relation to said openings and each including inner and outer plates in contacting engagement with its cooperating housing end wall and a stud joining the inner and outer plates and extending through the opening in said end wall, a rotary oper-

ating element in said housing and journaled in the studs of said bearings, abutments for limiting downward sliding of said bearings, and means yieldably resisting upward movement of said bearings and operating element. ¹⁰

In testimony whereof I affix my signature.

CLAUDE E. AYRES. [L.S.]
